CLOTHES HANGER

Earl C. Beard, Mishawaka, Ind., assignor of one-half to Anna M. Beard, Mishawaka, Ind.

Application March 14, 1934, Serial No. 715,398

7 Claims. (Cl. 24—137)

This invention relates to clothes hangers and particularly to hangers made in part of resilient material so formed that the clothes or articles to be supported thereby will not be injured.

The principal object of my invention is to provide a hanger having a spring metal base or frame covered with a rubber body formed to provide jaws adapted to firmly grip the article to be suspended therefrom.

A further object is to provide a hanger having rubber jaws so formed that they will not injure or leave any marks or indentations on the articles suspended thereby even though the texture of such articles be of very delicate or light material.

Another object is to provide a hanger which may either be suspended from a suitable support or inserted over a line and in either case clamp the article to be supported between the jaws thereof.

Another object is to provide a hanger having a U-shaped spring metal frame or base provided with handles extending from the closed end thereof and having a rubber body covering the free ends of the frame, the rubber being slotted between the spring ends to provide jaws for firmly gripping any article to be inserted therebetween.

The above being among some of the objects of the present invention, the same further resides in certain details of construction, methods of manufacture, and arrangements of parts, which will be apparent from the detailed description to follow.

Heretofore various types of hangers and clothes pins have been used but so far as I am aware all of these devices have been unsuitable for carrying delicate fabrics because of compression or indentation marks left on the article by such hangers or because of damage done to the fabric by the metal contacting therewith. I have provided a hanger or fastener which is suitable as a suspending means for delicate articles such as silk lingerie or stockings and yet which is sufficiently strong and rugged for supporting heavier articles when considerable weight is imposed on the hanger.

In order that others may understand my invention and the use and manufacture thereof, reference may be had to the annexed drawing and to the detailed description to follow. Referring to the numbered parts of the drawing in which like numerals refer to like parts throughout the several views,

Fig. 1 is a side elevational view of one construction embodying my invention, having a fragmentary portion of an article suspended thereby.

Fig. 2 is an end elevational view of the construction shown in Fig. 1.

Fig. 3 is a sectional view taken on the line 3—3 of Fig. 2.

Fig. 4 is a transverse sectional view taken on the broken sectional line 4—4 of Fig. 3.

Fig. 5 is a view similar to Fig. 1, showing a modified form of my invention, certain parts being broken away and in section to better illustrate the construction thereof.

Fig. 6 is a transverse sectional view taken on the line 6—6 of Fig. 5.

Fig. 7 is a view similar to Fig. 1, showing a further modification of my invention.

Figs. 8 and 9 shows forms of handles which may be substituted for those illustrated in the previous views.

Referring particularly to Figs. 1 to 4 inclusive, I have shown a hanger or fastener having a U-shaped spring metal member 10 which preferably has the free ends bent outwardly at 11. Handles 12 formed to be conveniently gripped by the operator are secured to the spring 10 in any suitable manner, as, for example, by spot-welding indicated at 13.

As best shown in Figs. 1 and 2, the spring 10 except the closed end thereof, and a portion of the handles 12 attached to the spring are covered with a rubber body 14 through which extends the hole 15 and which is slotted at 16 to provide a pair of jaws 17 between which an article A such as, for example, wearing apparel may be inserted and firmly gripped thereby. The hole 15 is provided to prevent tearing of the rubber as the jaws 17 are opened by forcing the ends of the handles 12 toward each other and also to provide a means whereby the hanger may be inserted over a rod or clothes line B.

The rubber body 14 is preferably formed of relatively soft rubber molded into the desired shape and vulcanized to the legs of the U-shaped spring 10 and to the lower ends of the handles 12. Through numerous tests which have been made, it has been found desirable to position the closed end of the spring 10 outwardly of the rubber body 14, as is clearly illustrated in Figs. 1 and 3, to thus permit for easier movement of the jaws 17 and reduce the strain which would otherwise be imposed upon the rubber body if the closed end of the spring were mounted within that body. I also prefer to provide a recess 18 in the rubber body adjacent to the closed end of the spring 10 which will permit the rubber to cold flow at that point when the jaws 17 are opened to thereby relieve the stresses on the rubber body which

would otherwise occur. As previously stated, the free ends of the spring 10 are bent outwardly at 11 which will tend to prevent the rubber from tearing away from the spring; however, the outwardly bent ends may be dispensed with if so desired.

In Figs. 5 and 6, I have shown a slightly modified form of my invention in which the U-shaped spring member 20 is slotted at 21 and the metal folded back on itself at 22 to provide the handles 23, the folded over metal being spot-welded if so desired. As illustrated, the free ends of the spring 20 are preferably bent outwardly at 24. In this construction, the spring is covered with the rubber body 14, as in the previous construction, which also has a hole 15 extending therethrough to receive a wire or clothes line B, and which is slotted at 16 to provide the jaws 17, and is provided with a recess 18 to permit of the more ready compression of the rubber body when the jaws are opened.

In Fig. 7, I have shown another modified form of my invention in which I provide two spring leaves 25 over which is formed the rubber body 14 having a hole 15 therethrough and slotted at 16 to provide the jaws 17, and provided with a recess 18 as heretofore described. The spring members 25 are made of sufficient length to provide handles 26 which are preferably connected by the member 27 formed of spring material and secured thereto by the rivets 28. Although I have shown rivets for attaching the spring member 27 to the springs 25, it will be understood that other fastening means may be provided as, for example, spot-welding.

In the views previously described, the handles are shown as rectangular bars; however, either or both of them may be formed as shown in Figs. 8 and 9, with a bent over end 29 or with a hole 30 extending therethrough. Either or both of the handles may be bent over at 29, as shown in Fig. 8, so that the hanger or fastener may be hooked over any suitable support or they may have the hole 30 through which a line or rod may be passed. In either case, the handles may be moved toward each other to thereby open the jaws 17 to receive the article to be supported therebetween.

The spring members are preferably formed of material which is sufficiently stiff to cause the adjacent faces of the jaws 17 of the rubber body to exert sufficient friction against the article to be supported so that the member carried thereby even though of considerable weight will not readily be detached therefrom. As the rubber body is preferably made of relatively soft rubber and as no metal can touch the article to be suspended from the hanger, it will be apparent that articles made of very light or delicate material will not be injured thereby, nor will the fasteners leave any compression or indentation marks on the article. Also, it will be understood that the fasteners can be made in a variety of colors if so desired for decorative purposes.

Although I have shown three modifications of my invention, it will be well understood by those skilled in the art that other changes such as

changes in proportion, form or shape may be resorted to without departing from the spirit and substance of my invention, the scope of which is to be measured entirely by the scope of the joined claims.

What I claim is:

1. A clothes hanger comprising, spaced flat metal spring portions, a rubber body covering said spring portions, means connecting said spring portions exteriorly of said rubber body, and handles connected with said spring portions extending outwardly from said rubber body, said rubber body being slotted intermediate said spring portions to provide jaws to receive an article to be supported thereby.

2. A clothes hanger comprising, a U-shaped spring, handles attached to each of the legs of said spring extending substantially parallel therewith away from the free ends thereof, and a rubber body covering the free ends of said spring, and the portions of the handles adjacent to said spring, said rubber body being slotted to provide jaws to receive an article to be supported thereby.

3. A device of the class described comprising, spaced flat metal spring members, a rubber body formed to provide jaws covering and vulcanized to said spring members, a flat metal spring portion exteriorly of said rubber body connecting said spring members, and handles attached to said spring members extending outwardly beyond said rubber body for opening said jaws.

4. A device of the class described comprising, a U-shaped spring, a rubber body slotted to form jaws covering and vulcanized to the free ends of said spring, the closed end of said spring being exposed, and handles attached to said spring extending outwardly beyond said rubber body for opening said jaws.

5. A device of the class described comprising, a U-shaped spring, a rubber body having a rod receiving hole extending therethrough and slotted from said hole to an edge of said body to form jaws covering and vulcanized to the free ends of said spring, the closed end of said spring being exposed, and handles attached to said spring for opening said jaws extending into and vulcanized to said rubber body.

6. A device of the class described comprising, a U-shaped spring, handles bent outwardly from the side faces of said spring forming slots therein, and a rubber body slotted to form jaws filling the slots formed in said spring by said handles and also covering and vulcanized to the free ends of said spring, the closed end of said spring being exposed.

7. A clothes hanger comprising, a U-shaped spring, a U-shaped rubber body covering and vulcanized to the free ends of said spring, the closed end of said spring being exposed, handles attached to said spring extending outwardly beyond said rubber body for spreading apart the legs of said rubber body, and a recess in said rubber body adjacent to the closed end of said spring to permit cold flow of said rubber body at that point when the legs thereof are spread apart.

EARL C. BEARD.
